UNITED STATES PATENT OFFICE

ARTHUR E. LITTLE, DECEASED, LATE OF ELYRIA, OHIO, BY AGNES G. LITTLE, ADMINISTRATRIX, OF AKRON, OHIO

DETACHABLE COUPLING FOR JOINTED FISHING RODS

Application filed December 27, 1928. Serial No. 328,779.

The objects of the invention are to provide a simple and efficient form of construction for a detachable coupling sleeve for the sections of a sectional fishing rod or pole.

5 The device is also quickly adjustable to rods of different diameters and is also so constructed that it can be instantly applied thereto and released therefrom, and also makes a joint that is more rigid than the other parts 10 of the rod, thus making the jointed rod stronger than a single rod.

Also locking means are provided that prevent the coupling from being detached from the sections of the rod.

15 The invention includes in a sheet metal sleeve open at one side throughout its length and provided with backwardly turned edges that are reversely and outwardly tapered from a medium point and are engaged by 20 means of wedge shaped clamping means that adjustably draw the longitudinal opposed edges of the sleeve together.

Also a sheet metal flap is employed to close the opening remaining between these edges.

25 With these and other features in view, the invention consists in the forms of construction illustrated in the accompanying drawing hereinafter more fully described and specifically pointed out in the claim.

30 In the accompanying drawing, Fig. 1 is a side elevation of the device applied to the sections of a rod, Fig. 2 is an enlarged transverse section thereof, Fig. 3 is a longitudinal section of Fig. 1 on the center line.

35 In these views A, A are the extremities of the rod sections, B is a sheet metal coupling open at one side and having its longitudinal edges C, C, outwardly and oppositely inclined from a medium point, D, D, and turned backward to form engaging means for the opposed wedge shaped plates F, F, which when moved alternately toward and away from the ends to compress the coupling sleeve about the ends of the sections, and to release the same.

45 Bosses G, G, upon the wedge plates may be added by means of which these plates can be moved by the fingers along the inclined edges of the sleeve.

50 Also a sheet metal flap H is secured underneath one longitudinal edge of the sleeve

which covers the open space between the edges and extends underneath the opposite edge, thus completely enclosing the extremities of the sections.

Also positive locking means are provided 55 to prevent the coupling sleeve from slipping from either extremity if the extremities should shrink from drying out in storage.

The locking means comprises a screw or pin I secured in each section at a measured distance from the ends thereof, and angle slots J in the outer transverse edges of the flap, into which the pins I, I, enter and are locked by a slight revolution of the rod sections.

Also each wedge plate is provided with a 65 shoulder K that engages with its respective pin when the wedges are drawn out to their clamping positions.

An annular inner bead L is centrally formed in the clamping sleeve against which 70 the extremities of the sections are thus positioned accurately in their places, so that the pins I, I, in the locking grooves will be securely clamped therein, and the sleeve will be equally extended over the rod extre- 75 mities.

Having described the invention what is claimed as new and is desired to be secured by Letters Patent is:

In a device of the character described, the 80 combination with the proximate extremities of a jointed rod, of a longitudinally slotted sleeve thereover, the longitudinal edges of said sleeve being reversely inclined from the center outwardly in both directions, wedge 85 plates slidably movable over said slot, inter-engaging means upon the meeting edges of said plates and sleeve, and a pin or screw in each rod, the outer ends of said sleeve being provided with angular slots for the reception of said pins, and each wedge plate being provided with a locking shoulder preventing the escape of said pins from said angular slots.

In testimony whereof, I affix my signature. 95

AGNES G. LITTLE,
Administratrix of the Estate of the Late
Arthur E. Little.
